KNITTING MACHINE

William C. Adams, Cincinnati, Ohio

Application September 30, 1946, Serial No. 700,193

15 Claims. (Cl. 66—16)

1

This invention relates to improvements in knitting machines, particularly such machines as may be used by children, convalescents and others in the home for knitting a cord or rope from yarn.

Some attempts have been made to provide knitting machines for the purpose of home occupation, but these machines required the user to do more than just operate the machine, with the result that the knitted cord or rope was not uniform and frequently faulty. The knitting cord or rope of the present machine can be connected to one another to form garments, headgear, purses and an infinite field of articles.

The principal object of the present invention is the provision of a knitting machine that is simple to operate and is positive in its operation and substantially fool proof, whereby a uniform knitted product results.

Another object of the present invention is the provision of a knitting machine composed of only those elements necessary for continuous operation in the production of a knitted cord or rope.

It is also the object of this invention to provide a knitting machine of the class herein above set forth, wherein the operator is required to do nothing but furnish the motive power, namely, rotate a handle or crank, allowing the machine to otherwise automatically function.

It is a still further object of the present invention to provide a self-contained knitting machine wherein the knitted rope or cord is uniform in size and texture, since the human element does not enter into the production of the product except to furnish the motive power as set forth in the preceding paragraph.

Other objects and advantages of the present invention should be readily apparent by reference to the following specification, considered in conjunction with the accompanying drawings forming a part thereof, and it is to be understood that any modification may be made in the exact structural details there shown and described, within the scope of the appended claims, without departing from or exceeding the spirit of this invention.

In the drawings:

Fig. 1 is a side elevational view of a knitting machine embodying the principles of this invention.

Fig. 2 is an end elevation of the machine illustrated in Fig. 1, and as seen from the right hand end thereof in Fig. 1.

Fig. 3 is a top plan view of the machine as seen in Fig. 1.

2

Fig. 4 is a transverse sectional view through the machine as seen from line 4—4 on Fig. 2.

Fig. 5 is a vertical sectional view, on a larger scale, of the machine taken on line 5—5 on Fig. 1.

5 Fig. 6 is a fragmentary view, partly in section and partly in elevation, showing certain parts of Fig. 5, as seen particularly from line 6—6 on Fig. 5.

Fig. 7 is a fragmentary view, partly in section 10 and partly in elevation, of the parts of Fig. 5, showing same in a second position of operation.

Fig. 8 is a transverse sectional view through certain parts of Fig. 5 as seen from line 8—8 on said Fig. 5.

15 Fig. 9 is a transverse sectional view similar to Fig. 8, taken in a plane below that of said Fig. 8, on line 9—9 on Fig. 5.

Throughout the several views of the drawings similar reference characters are employed to 20 note the same or similar parts.

The knitting machine of the present invention is mounted on a base or support 10 illustrated in the drawings as stamped from sheet metal, and comprises a platform 11, from the longitudinal 25 edges of which depends sides 12 and 13. The lower end of the base sides 12 and 13 are outwardly disposed to provide feet 14 and 15 on which the base primarily rests. Depending from the foot 15, which is along the front side of the 30 base, is a flange 16.

It is contemplated that the knitting machine of the present invention will be used on a table or other support so that the operator may be seated in front thereof; with the machine preferably 35 at a corner of said table or other support. In this position the flange 16 will engage an edge of said table or other support to act as an anchor against displacement of the machine in a rearward direction during operation.

40 In order to anchor the machine against movement to the side or endwise, the base platform 11 has depending therefrom a tongue 17 to engage the right hand edge of the table or other support from that engaged by the flange 16. The tongue 45 17 is conveniently formed from the body portion of the platform 11 and thereby results in a notch or opening 18 in the right hand end of the platform 11. As will be later apparent this notch 18 is employed for the finished knitted cord or rope 50 of the machine to pass there-through.

Secured to and upstanding from the base platform 11 is a bearing block 19 having secured therein, see Fig. 5, a bushing 20, secured in position by screws or the like 21 passing through a 55 radial flange 22 at the forward end of the bushing

20. Mounted in the bearing bushing 20 is the shaft 23 of a crank 24 which has at its other end a knob 25, through which the operator actuates the mechanism of the knitting machine. The shaft 23 is held against axial movement in one direction by an abutment 26 thereon which engages the forward face of the bearing flange 22. The axial movement of the shaft 23 in the other direction is prohibited by a set screw, or the like 27, carried by the operating member 28 to be later described, it being understood that the set screw 27 impinges on the said shaft 23.

Secured to and upstanding from the bearing block 19 is a face plate or support 29 having screwed to it, at its upper end, a second bearing block 30. The bearing block 30 is provided therein with a bearing bore 31 for the knitting needle sleeve 32. In its upper end the bearing block 30 is provided with a counter-bore 33, concentric with the bearing bore 31.

Disposed in the bore 31 of the bearing block 30, as intimated above, is the knitting needle sleeve 32 which is substantially cylindrical throughout its length, having, however, the upper portion thereof of a diameter slightly less than that portion within the bore 31, thereby providing on the sleeve 32 a shoulder 34. The needle sleeve 32 is provided throughout its length with notches or splines 35 which may vary in number, depending upon the size of the finished knitted cord or rope desired.

The number of such notches 35 also determines the cross section of the knitted cord or rope desired. As illustrated in the drawings the sleeve 32 is provided with four notches, in each of which is a knitting needle, and it should be here noted that four needles produce a satisfactory product for substantially any further use.

The knitting needles utilized with this machine are of a kind now being commercially produced, and of a well known construction. One of such needles is clearly illustrated in Fig. 5 and as there shown, comprises a shank 36, the lower end of which is bent on itself to form an outwardly projecting lug, commercially known as the needle butt 37. The upper end of the shank 36 is bent to form a hook 38 having a sharp point 39. The shank 36 has its upper portion of a smaller dimension, as illustrated at 40, and which fact is here pointed out, and whose function will be later described in detail. The said shank portion 40 just below the needle hook is flattened to provide a pair of ears 41, between which is pivotally mounted a latch 42.

Each knitting needle is disposed in its slot 35 in such a manner as to slide there through, as will later be made clear. In order to retain the knitting needles in their slots use is made of a collar 43, having a reduced projecting portion 44 as seen in Fig. 5. The collar 43 is further provided with notches 44' which, as will later be made clear correspond to the number of needles used with the machine. Collar 43 is split to provide a passageway 45 of a width equal to the width of the needle shank 36.

In order to mount the needles in their respective slots the collar 43 is positioned on the sleeve 32 near the upper end thereof to embrace needle shank portions 46, and rotated to align the passageway 45, successively, with the sleeve slots, whereupon a needle butt 37 is passed through the passageway 45 and the needle shank 36 disposed into its slot 35. As just intimated this operation of the collar 43 is gone through with for each slot until a separate needle is mounted in each

5 of the needle slots. The collar is then actuated or rotated about the sleeve 32 to dispose the passage way 45 at a point intermediate two adjacent needles, which will bring the notches in the collar into alignment with the needle shanks. It is preferable that the parts of the machine be in the positions illustrated in Fig. 5, whereupon the collar 43 is actuated axially of the sleeve 32 to cause the reduced portion 44 thereof to force 10 all of the needle butts 37 against the base 46 of the counter-bore 33. This axial movement of the collar is permitted by the passage of collar notches 44' over the enlarged portions of the needle shanks 36. The collar 43 is now secured to the sleeve against rotative and axial movement by a dog or clamp screw 47. It will now be evident that the collar 43 retains the needles in their respective slots or splines without interfering with their reciprocation.

20. Pressed into the sleeve 32, and projecting there below, is a tube 48 which has screwed to its lower end an index head 49. The index head 49 is an index collar like member having projecting therefrom as many index fingers 50 as there are needle 25 slots in the sleeve 32 in the machine illustrated in the drawings; there are four such index fingers 50. Surrounding the projecting portion of the tube 48 is an expansion coil spring 51, abutted on its one end with index collar 49, and on its 30 other end with a plate 52 secured to bearing block 33 and spanning the opening or aperture therein.

The expansion spring 51 yieldably holds the tube 48 and sleeve 32 in their lower most position, which is determined by a substantially heart-shaped cam 53 carried by the crank shaft 23. The cam 53, see particularly Figs. 6 and 7, has a low point 54, followed by a rise 55 to its high point 56, whereupon the cam 53 drops as at 57 to the low point 54. By rotating the cam 53 in the direction of the arrow 58 in Fig. 6, it will be noted that the tube 48 and parts connected therewith are upwardly elevated by the cam rise 55 until the high point 56 is reached. At this time the spring 51 is compressed from its expanded position in Fig. 5 to the position thereof illustrated in Fig. 7. The continued rotation of the cam 53 in the direction of the arrow 58 now presents the decline 57 to the index collar 49, thereby permitting the spring 51 to expand and return 50 the tube 48 to its lower most position of Fig. 5.

The cam 53 is secured to the member 28 which, as illustrated in Fig. 5, is somewhat U-shaped in longitudinal cross section, thereby providing a rear flange 59 through which suitable screws or the like 60 pass into the cam 53. The front flange 61 of the member 28 is extended as a finger 62 which indexes the needle sleeve so as to bring into operation each of the needles in succession. Base or flanges 59 and 61 are connected to one 60 another by a base member 63 which carries the set screw 21 securing the said member and cam 53 to the shaft 23 for operation by crank 24.

Secured to the upper surface of the upper bearing block 30 is a plate 64 which has a projecting portion 65 to overlie the bearing block counter-bore 33 for a space not exceeding 90 degrees thereof, and illustrated most clearly in Fig. 8.

The plate projection 65 is to overlie the butts 37 of the knitting needles when they are successively brought there-under, and the said projection effects the reciprocation of the needles successively through the sleeve slots 35.

Secured to the machine base 10 behind the knitting mechanism is a canister or container 66 provided with removable cover 67 which may

conveniently take the form of a slip cover. Substantially, centrally, of the cover 67 there is provided an aperture 68 through which extends the yarn 69 from a ball or spool suitably housed in the canister 66. The yarn 69 in passing from the canister extends through an anti-twisting device indicated in general in the drawings by the reference numeral 70. This anti-twisting device may take any usual form, that shown in the drawings comprising a base member 71, having upstanding therefrom a pair of eyes 72 and 73, through which the yarn passes. The yarn extends from the anti-twisting device 70 to the yarn feeding or holding arm 74 which as seen in Figs. 7 and 5 is secured to one side of the bearing block 30 by means of screws or bolts 75. The yarn feeding arm 74 extends to a point in operative relation to the knitting needle hooks 38 and is there provided with a suitable guide or eye 76 through which the yarn passes to the needles. The knitted cord or rope 77 extends through the hollow interior of the tube 48 and needle sleeve 32 and passes below the machine and supporting table top by passing through the notch or opening 18 in the base platform 11. Secured to the knitted cord or yarn 77 below the machine is a tension supplying device indicated in general in the drawings by the reference numeral 78. Any suitable or desirable mechanism may be employed as the tensioning mechanism, that illustrated in the drawings comprises a substantially rectangular weight having an aperture 79 therein and a V-shaped notch 80. In use the knitted cord or rope is first passed through the aperture 79 and then secured by being forced into the apex of the V-notch 80.

The operation of the knitting machine is as follows:

A ball or spool of yarn is placed in the canister 66, with its free end passing through the aperture 68 therein and then through the anti-twisting device 70, to the eye or passageway 76 in the yarn feeding or holding arm 74. The yarn is then looped successively around the needles, starting with the needle substantially, immediately, in front thereof, and passing to successive needles in a counter-clockwise direction as seen in Fig. 3. After the yarn has been looped it is placed within the hook 38 of the first needle, or that needle whose butt is beneath projecting portion 65, whereupon the end of the yarn is passed downwardly through the tube 48 to a point immediately below the base platform 11 and the tension mechanism or device 78 secured thereto, whereupon the machine is ready for operation.

The operator rotates the crank 24 in a clockwise direction as seen in Fig. 1, thereby rotating the cam 53, as above described, for moving the tube 48 and needle sleeve 32 upwardly, the needles being frictionally held by the collar 43 to the sleeve 32, move with said sleeve, except that needle whose butt is beneath the projecting portion 65 of plate 64 which is held in its lowermost position or caused to slide relatively through its slot 35. This causes the yarn to be removed from the needle shank 36 by first closing the latch 42 and passing there-over as well as over the hook 38. In other words, the hook 38 which has the yarn disposed therein, pulls the said yarn through the loop previously made on its shank. The drawing of the yarn through the loop was accomplished by the time the tube 48 and parts carried thereby reached their uppermost position, illustrated in Fig. 7, whereupon the tube 48 descends

through the action of the spring 51 as pointed out above. This downward movement of the tube 48 causes that portion of the yarn within the hook 38 to leave said hook and be in effect looped around the shank 36 of its needle. At this time, the cam 53 has made almost a complete revolution, as has the member 28 and the index finger 62, whereupon the index finger 62 engages the next index pin 50 for rotating the sleeve 48 and needle sleeve 32, to place the butt of the next needle under the projection 65 of the plate 64. As soon as this occurs the tube 48 and needle sleeve are actuated through another cycle for effecting the knitting by the second needle. This cycle of operation continues so long as the crank 24 is rotated.

It has been found that the machine has a slight tendency to slide while being operated, and to avoid this, use is made of anti-slide devices on the flanges 14 and 15 which conveniently take the form of a rubber band 81 encircling each of the flanges 14 and 15.

It is believed now evident that there has been provided a knitting machine which will accomplish the objects initially set forth.

What is claimed is:

1. In a device of the class described the combination of a base, a support carried by said base, a knitting needle sleeve having slideably mounted therein a plurality of knitting needles, said sleeve being mounted in the support for rotative and axial movement relative thereto, and means for alternately rotating and axially shifting said sleeve.
2. In a device of the class described the combination of a base, a support carried by said base, a knitting needle sleeve having slideably mounted therein a plurality of knitting needles, said sleeve being mounted in the support for rotative and axial movement relative thereto, and means for alternately rotating and axially shifting said sleeve, including a manually operable crank.
3. In a device of the class described a sleeve having mounted therein a plurality of knitting needles, said needles having independent reciprocating movement relative to the sleeve, a support for said sleeve and relative to which the sleeve is mounted for rotative and axial movement, positive means for axially shifting the sleeve in one direction, yielding means for axially shifting the sleeve in the opposite direction, and timed means operable simultaneously with one of the positive and yielding sleeve axial shifting means for rotating the sleeve.
4. In a device of the class described a sleeve having mounted therein a plurality of knitting needles, said needles having independent reciprocating movement relative thereto, a support for said sleeve and relative to which the sleeve is mounted for rotative and axial movement, positive means for axially shifting the sleeve in one direction, yielding means for axially shifting the sleeve in the opposite direction, timed means operable simultaneously with one of the positive and yielding sleeve axial shifting means for rotating the sleeve, and means for effecting the reciprocation of said needles successively relative to the sleeve during the axial movement thereof.
5. In a device of the class described the combination of a knitting needle sleeve adapted to support a plurality of knitting needles, said needles being adapted for independent reciprocative movement relative to the sleeve, means for supporting said sleeve for rotative and axial move-

ment, a cam for effecting the axial movement of the sleeve in one direction, yielding means for effecting the axial movement of the sleeve in the opposite direction, and means for rotating the sleeve prior to the axial movement thereof by one of the cam and yielding sleeve moving means.

6. In a device of the class described the combination of a knitting needle sleeve adapted to support a plurality of knitting needles, said needles being adapted for independent reciprocative movement relative to the sleeve, means for supporting said sleeve for rotative and axial movement, a cam for effecting the axial movement of the sleeve in one direction, yielding means for effecting the axial movement of the sleeve in the opposite direction, means for rotating the sleeve prior to the axial movement thereof by one of the cam and yielding sleeve moving means, and a common means for effecting the simultaneous operation of the cam and sleeve rotating means.

7. In a device of the class described the combination of a knitting needle sleeve adapted to support a plurality of knitting needles, said needles being adapted for independent reciprocative movement relative to the sleeve, means for supporting said sleeve for rotative and axial movement, a cam for effecting the axial movement of the sleeve in one direction, yielding means for effecting the axial movement of the sleeve in the opposite direction, means for rotating the sleeve prior to the axial movement thereof by one of the cam and yielding sleeve moving means, and a common means for effecting the simultaneous operation of the cam and sleeve rotating means, comprising a manually operable crank.

8. In a device of the class described the combination of a knitting needle sleeve adapted to support a plurality of knitting needles, said needles being adapted for independent reciprocative movement relative to the sleeve, means for supporting said sleeve for rotative and axial movement, a cam for effecting the axial movement of the sleeve in one direction, yielding means for effecting the axial movement of the sleeve in the opposite direction, means for rotating the sleeve prior to the axial movement thereof by one of the cam and yielding sleeve moving means, a common means for effecting the simultaneous operation of the cam and sleeve rotating means, and means for holding one of said needles against movement during the axial movement of the sleeve.

9. In a device of the class described the combination of a base, a support carried by and upstanding from said base, a pair of bearing blocks, located one above the other, secured to and projecting from said support, a knitting needle sleeve mounted in the upper of said bearing blocks for axial movement and intermittent rotary movement relative thereto, said sleeve having formed longitudinally thereof a plurality of slots, each receiving a knitting needle therein, and which needles are each adapted to reciprocate in its slot, means for effecting the axial movement of the sleeve in the bearing block, means for effecting the intermittent rotation of the sleeve, means carried by the sleeve for holding the needles in their slots for movement therewith, and means carried by the upper bearing block for causing the reciprocation of a needle relative to the sleeve during the axial movement of said sleeve.

10. In a device of the class described the combination of a base, a support carried by and upstanding from said base, a pair of bearing blocks, located one above the other, secured to and pro-

jecting from said support, a knitting needle sleeve mounted in the upper of said bearing blocks for axial movement and intermittent rotary movement relative thereto, said sleeve having formed longitudinally thereof a plurality of slots, each slot receiving a knitting needle therein, and which needles are each adapted to be reciprocated, respectively, in its slot, a collar surrounding said sleeve for retaining the needles in their slots, said collar having a passageway therethrough whereby the needles may be disposed within their slots, said needles each having integral therewith a butt adapted to be engaged to said collar for positioning the same relative to the sleeve, means carried by the lower of said blocks for effecting the axial movement of the sleeve and its intermittent rotation for imparting said motions to the needles carried by the sleeve, and means for holding the needles, successively, against movement with the sleeve in an axial direction to thereby relatively reciprocate the needles in their respective slots.

11. In a device of the class described the combination of a base, a support carried by and upstanding from said base, a pair of bearing blocks, located one above the other, secured to and projecting from said support, a knitting needle sleeve mounted in the upper of said bearing blocks for axial movement and for intermittent rotary movement relative thereto, said sleeve having formed longitudinally thereof a plurality of slots, each slot receiving a knitting needle therein, and which needles are each adapted to be reciprocated, respectively, in its slot, a collar surrounding said sleeve for retaining the needles in their slots, said collar having a passageway therethrough whereby the needles may be disposed within their slots, said needles each having integral therewith a butt adapted to be engaged by said collar for positioning the same relative to the sleeve, means carried by the lower of said blocks for effecting the axial movement of the sleeve and its intermittent rotation for imparting said motions to the needles carried by the sleeve, means for holding the needles, successively, against movement with the sleeve in an axial direction to thereby relatively reciprocate the needles in their respective slots, comprising a depression in the bearing block into which the needle butts are inserted by the collar, and an abutment overlying said recess to engage the needle butts and thereby cause the relative reciprocation of the needles in their respective slots.

12. In a device of the class described the combination of a base, a support carried by and upstanding from said base, a pair of bearing blocks, located one above the other, secured to and projecting from said support, a knitting needle sleeve mounted in the upper of said bearing blocks for axial movement and for intermittent rotary movement relative thereto, said sleeve having formed longitudinally thereof a plurality of slots, each slot receiving a knitting needle therein, and which needles are each adapted to be reciprocated, respectively, in its slot, a collar surrounding said sleeve for retaining the needles in their slots, said collar having a passageway therethrough whereby the needles may be disposed within their slots, said needles each having integral therewith a butt adapted to be engaged by said collar for positioning the same relative to the sleeve, means carried by the lower of said blocks for effecting the axial movement of the sleeve and its intermittent rotation for imparting said motions to the needles carried by the sleeve, means for holding the needles success-

75 the sleeve, means for holding the needles suc-

sively against movement with the sleeve in an axial direction to thereby relatively reciprocate the needles in their respective slots, and manually operable means for actuating the sleeve rotating and axially shifting means.

13. In a device of the class described the combination of a base, a support carried by and upstanding from said base, a pair of bearing blocks, located one above the other, secured to and projecting from said support, a knitting needle sleeve mounted in the upper of said bearing blocks for axial movement and for intermittent rotary movement relative thereto, said sleeve having formed longitudinally thereof a plurality of slots, each slot receiving a knitting needle therein, and which needles are each adapted to be reciprocated, respectively, in its slot, a collar surrounding said sleeve for retaining the needles in their slots, said collar having a passageway there through whereby the needles may be disposed within their slots, said needles each having integral therewith a butt adapted to be engaged by said collar for positioning the same relative to the sleeve, means carried by the lower bearing block for effecting the axial movement of the sleeve and its intermittent rotation for imparting said motions to the needles carried by the sleeve and means for holding the needles successively against movement with the sleeve in an axial direction to thereby relatively reciprocate the needles in their respective slots, said sleeve axial movement means comprising a peripheral cam in operative engagement with said sleeve to effect its movement in one direction, and a spring for holding the sleeve in peripheral contact with the cam and effecting its movement in the opposite direction.

14. In a device of the class described the combination of a base, a support carried by and upstanding from said base, a pair of bearing blocks, located one above the other, secured to and projecting from said support, a knitting needle sleeve mounted in the upper of said bearing blocks for axial movement and for intermittent rotary movement relative thereto, said sleeve having formed longitudinally thereof a plurality of slots, each slot receiving a knitting needle therein, and which needles are each adapted to be reciprocated, respectively, in its slot, a collar surrounding said sleeve for retaining the needles in their slots, said collar having a passageway therethrough whereby the needles may be disposed within their slots, said needles each having integral therewith a butt adapted to be engaged by said collar for positioning the same relative to the sleeve, means carried by the lower of said blocks for effecting the axial movement of the sleeve and its intermittent rotation for imparting said motions to needles carried by the sleeve and means for holding the needles, successively, against movement with the sleeve in an axial direction to thereby relatively reciprocate the needles in their respective slots, said sleeve axial movement means comprising a peripheral cam in operative engagement with said sleeve to effect

its movement in one direction, and a spring for holding the sleeve in peripheral contact with the cam and effecting its movement in the opposite direction, said intermittent rotating means comprising an index head carried by said sleeve, indexing fingers associated with and projecting from said index head, and a rotating arm for engagement with successive indexing fingers to thereby intermittently rotate the sleeve.

10 15. In a device of the class described the combination of a base, a support carried by and upstanding from said base, a pair of bearing blocks, located one above the other, secured to and projecting from said support, a knitting needle sleeve mounted in the upper of said bearing blocks for axial movement and for intermittent rotary movement relative thereto, said sleeve having formed longitudinally thereof a plurality of slots, each slot receiving a knitting needle therein, and 15 which needles are each adapted to be reciprocated, respectively, in its slot, a collar surrounding said sleeve for retaining the needles in their slots, said collar having a passageway there through whereby the needles may be disposed within their slots, said needles each having integral therewith a butt adapted to be engaged by said collar for positioning the same relative to the sleeve, means carried by the lower of said blocks for effecting the axial movement of the sleeve and its intermittent rotation for imparting said motions to the needles carried by the sleeve, means for holding the needles, successively, against movement with the sleeve in an axial direction to thereby relatively reciprocate the needles in their respective slots, said sleeve axial movement means comprising a peripheral cam in operative engagement with said sleeve to effect its movement in one direction, and a spring for holding the sleeve in peripheral contact with the cam and effecting 20 its movement in the opposite direction, said intermittent rotating means comprising an index head carried by said sleeve, indexing fingers associated with and projecting from said index head, and a rotating arm for engagement with successive indexing fingers to thereby intermittently rotate the sleeve, and a single means for simultaneously actuating said cam and rotating index arm.
